UNITED STATES PATENT OFFICE.

GEORGE R. FOX, OF PLAQUEMINE, LOUISIANA.

SPECULUM.

SPECIFICATION forming part of Letters Patent No. 596,399, dated December 28, 1897.

Application filed May 7, 1897. Serial No. 635,576. (No model.)

To all whom it may concern:

Be it known that I, GEORGE R. FOX, a citizen of the United States, residing at Plaquemine, in the parish of Iberville and State 5 of Louisiana, have invented certain new and useful Improvements in Speculums; and I do hereby declare the following to be a full, clear, and exact description of the invention, such as will enable others skilled in the art to which 10 it appertains to make and use the same.

My invention relates to speculums, and more particularly an irrigating vaginal speculum; and it consists of certain novel constructions, combinations, and arrangements of 15 parts, as will be hereinafter described and specifically claimed, whereby an instrument is produced all the parts of which can be conveniently taken apart and cleansed and rendered aseptic and again reassembled and 20 an outlet secured in the instrument for fluids while being used and the patient inspected.

In the accompanying drawings, Figure 1 is a perspective view of my improved speculum. Fig. 2 is a vertical longitudinal section 25 through the lower blade. Fig. 3 represents a collection of the different component parts of the instrument, showing details of construction.

My improved irrigating vaginal speculum 30 comprises in its construction the following main parts: an upper blade A, a lower blade B, a sliding fork C, a ratchet-bar D, and a screw E for holding the sliding fork C in position on the shank of the lower blade B. The upper blade A is somewhat similar in 35 construction to those used in other forms of speculums, except that it is fenestrated at a and is provided with a slot a' in its shank, through which the ratchet-bar D passes, and 40 has its shank end a⁴ roughened or corrugated to form a thumb-rest and prevent the thumb of the operator slipping when manipulating the instrument. The lower blade B is formed with a hollow shank or handle b, which is 45 corrugated at its rear or lower end for the attachment of a piece of rubber tubing F for conducting fluids therefrom. The lower blade B is made somewhat similar, but funnel-shaped at b² for conducting the fluids into the 50 hollow shank, and is also formed with a small ridge b³ to prevent the fluids flowing into the opening in the upper portion of said shank

from escaping. Making the shank of the lower blade hollow and so shaping it to conduct the fluid into said hollow portion is very 55 important, as it not only allows for the escape of the fluids while operating, but prevents the fluids from passing on to the hand or clothes of the operator.

While it is not new to provide a syringe 60 with escape-vents for fluids, so far as I am aware I am the first to provide a speculum with an irrigating construction, the parts being adapted to be held open and subject to inspection while the irrigation is taking place. 65 The outer surface of the lower blade B is flattened for the purpose of receiving the sliding fork C, and is provided on said surface at suitable points in its length with a small pin b⁴ and a longer threaded pin b⁵, the pins 70 working in the slots c c of the fork C, the former pin, b⁴, serving to guide the fork in its longitudinal movement upon the lower blade and the latter pin being designed to receive a thumb-screw c' for holding the fork C in 75 any adjusted position on the lower blade, as shown in the drawings. A ring b⁶ is secured on the under side of the lower blade B, into which a finger can be inserted while using the instrument. The fork C comprises a 80 shank c² and upwardly-extending curved arms c³, the under side of the fork being flattened to rest and move smoothly upon the outer flattened surface of the lower blade B. The shank of the fork is slotted, as at c⁴ c⁵, 85 to receive the pins b⁴ and b⁵, and is also provided with a bar or pin c⁶ to receive the lower end of the ratchet-bar D, as will be herein-after described. The upper blade A is pivoted between the curved arms c³ of the fork, 90 the arms being perforated for that purpose, and the upper blade being provided on one side with a projection a² to fit into one of the perforations of the sliding fork C, the said upper blade being held in place on its other 95 side by means of a screw-pin passed through the other perforation in the upper blade. By this construction the upper blade can be readily disconnected from the sliding fork for the purpose of cleansing and as readily assembled again. The ratchet-bar D is formed at its lower end with an open eye d, which fits around the pin or bar c⁶ and has its upper end passed through the slot a' and is 100

adapted to engage a pin or bar a^3 , provided in said slot a' .

It will be obvious that when it is desired to adjust the upper blade independently of the lower blade it can be readily accomplished by disengaging the ratchet-bar from the pin a^3 and pressing down upon the roughened thumb piece or shank a^4 , and that said upper blade can be held in such adjusted position 10 by allowing the pin or bar a^3 to engage the proper ratchet-tooth, and that this operation can be performed with one hand, the ratchet-bar being in close proximity to the roughened thumb-piece. It will also be observed that 15 when it is desired to separate the upper and lower blades vertically it can be readily accomplished by loosening the thumb-nut E and sliding the fork the proper distance and then again securing it in position by means 20 of said thumb-screw, the sliding of the fork being facilitated by reason of a projection or ridge c^5 , against which the thumb rests in pushing up the fork.

Having now described my invention, what 25 I claim as new, and desire to secure by Letters Patent, is—

1. An irrigating-speculum having a blade provided with a tubular shank or stem hollow throughout its entire length and open at 30 both ends, both of the open ends connecting directly with the hollow portion and forming a continuous passage for conducting fluids through the same away from the speculum, the shank or stem being adapted to be grasped 35 by the hand of the operator for drawing down the parts of the patient and allowing the discharge to pass through the shank or stem and escape out the lower end of the stem while the speculum is in position within the patient, 40 substantially as described.

2. A speculum comprising in its construction a lower blade provided with a hollow shank or stem open at both ends for conducting fluids through the stem away from the 45 speculum while the speculum is in an adjusted position and the parts of the patient are being inspected, a fork longitudinally slideable on said lower blade, means for securing the fork to the lower blade at the de-

sired adjusted position, and an upper blade 50 pivoted to the outer end of the fork and means adapted to engage and hold the upper blade at the desired adjusted position, substantially as described.

3. A speculum comprising in its construction a lower blade, provided with a hollow shank or stem and a flaring funnel-shaped opening, a fork longitudinally slideable on the said lower blade, means for securing the fork to the lower blade at the desired adjusted 60 position, and an upper blade pivoted to the outer end of the fork, and a ratchet-bar connected to the sliding fork and adapted to engage and hold the upper blade at the desired position, the construction and arrangement 65 being such that the parts of a patient can be inspected and irrigated while the speculum is in place and in an adjusted position, substantially as described.

4. A speculum comprising in its construction a lower blade, provided with a hollow shank or stem for conducting fluids through the speculum while the speculum is in an adjusted position and the parts of the patient are being inspected, a rubber tube attached 70 to the rear end of the said hollow stem, a fork longitudinally slideable on said lower blade, means for securing the fork to the lower blade at the desired adjusted position, and an upper blade pivoted to the outer end of the fork 80 provided with a slot and a ratchet-bar secured at its lower end to the sliding fork and passing through the slot in the upper blade and adapted to engage and hold the same in an adjusted position, substantially as described. 85

5. An irrigating-speculum comprising in its construction a lower blade provided with a hollow shank or stem open at both ends for conducting fluids through the stem away from the speculum, an adjustable upper blade, and 90 means for holding the upper blade in an adjusted position, substantially as described.

In testimony whereof I hereunto affix my signature in presence of two witnesses.

GEORGE R. FOX.
